The ornamental design for a pair of hanger bar mounting heads, as shown and described.

DESCRIPTION

FIG. 1 is a front perspective view of a pair of hanger bar mounting heads, showing our new design;

FIG. 2 is a enlarged partial front left perspective view of the right mounting head for the pair of hanger bar mounting heads;

FIG. 3 is a front elevation view thereof;

FIG. 4 is a rear elevation view thereof;

FIG. 5 is a enlarged partial top plan view thereof;

FIG. 6 is a enlarged partial bottom plan view thereof;

FIG. 7 is a left-side elevation view thereof; and

FIG. 8 is a right-side elevation view thereof.

FIG. 9 is a enlarged partial front right perspective view of the left mounting head for the pair of hanger bar mounting heads;

FIG. 10 is a front elevation view thereof;

FIG. 11 is a rear elevation view thereof;

FIG. 12 is a enlarged partial top plan view thereof;

FIG. 13 is a enlarged partial bottom plan view thereof;

FIG. 14 is a enlarged partial left-side elevation view thereof; and,

FIG. 15 is a enlarged partial right-side elevation view thereof.

The broken lines shown in the figures represent unclaimed subject matter and form no part of the claimed design.
